United States Patent Office.

WILLIAM E. WHITING, OF PROVIDENCE, RHODE ISLAND.

Letters Patent No. 74,468, dated February 11, 1868.

IMPROVEMENT IN GAUGES FOR AUGERS.

The Schedule referred to in these Letters Patent and making part of the same.

TO ALL WHOM IT MAY CONCERN:

Be it known that I, WILLIAM E. WHITING, of the city and county of Providence, in the State of Rhode Island, have invented a new and useful Improvement in a Gauge to be Used in Boring; and I do hereby declare that the following is a full, clear, and exact description of the same, reference being had to the annexed drawings, making a part of the specification, in which—

Figure 1 is a perspective view of my invention drawn out.

Figure 2 is a section showing an auger attached.

Figure 3 represents my invention when closed.

Figure 4 is an end view, showing the set-screws used in fastening.

In the accompanying drawings, A, B, and C, fig. 1, are three tubes, made to slide one within the other, forming an auger or bit-gauge. These tubes have openings at their sides for the purpose of freeing the chips when in use. A and B are provided with two slots, made lengthwise, one side of each slot being plain, the opposite sides having notches, to be used in setting to any desired length, by means of pins, as shown in fig. 1. These pins are made to fit the notches, and when turned in, either prevents the gauge from closing or opening when in use. D, fig. 1, is a ring, fastened or cast to the upper end of A, and made a suitable thickness for set-screws to fasten to an auger or bit, as shown in figs. 2 and 4. E is a flange, fastened or cast to the lower end of C. This flange is used as a stop to prevent the auger or bit from cutting too deep, the under surface bringing up against the wood.

To use my invention, the flange E should be set the desired distance on the auger or bit, which can be done by turning the auger until the under surface of flange E is the desired distance from the cutting-end of auger or bit. This end of gauge is then fastened by means of set-screws, as shown in fig. 2. The pins being turned in their proper notches, the opposite end of gauge at D can be fastened to opposite end of auger or bit by set-screws or otherwise. It is then ready for use.

The advantages of my invention are, it can be adjusted to an auger or bit to bore any desired depth, and capable of fitting different sizes combined in one gauge; thereby saving the expense of making a gauge for each size auger or bit.

I do not claim fitting a piece of metal or wood to an auger or bit for a gauge, but

What I do claim, and desire to secure by Letters Patent of the United States, is—

The tubes A and C, in combination with the ring D and flange E, when constructed and arranged substantially as set forth and for the purpose specified.

WM. E. WHITING.
